UNITED STATES PATENT OFFICE.

HOWARD BRUCE, OF BALTIMORE, MARYLAND, ASSIGNOR TO THE BARTLETT HAYWARD COMPANY, OF BALTIMORE, MARYLAND, A CORPORATION OF MARYLAND.

SEALING-BELL FOR RETORT STAND-PIPES

1,171,384.

Specification of Letters Patent.

Patented Feb. 8, 1916.

Original application filed January 7, 1914, Serial No. 810,723. Divided and this application filed February 24, 1915. Serial No. 10,275.

To all whom it may concern:

Be it known that I, HOWARD BRUCE, a citizen of the United States, residing at Baltimore, in the State of Maryland, have 5 invented certain new and useful Improvements in Sealing-Bells for Retort Stand-Pipes, of which the following is a specification.

This invention relates to improvements in 10 sealing bells for standpipes of gas retorts, and the present application is a division of my co-pending application for patent filed January 7th, 1914, Serial Number 810,723.

One object of the invention is to provide 15 improved means for sustaining the sealing bell about the standpipe end.

Another object is to provide improved 20 means for accurately adjusting the lower edge of the sealing bell in the hydraulic main whereby to uniformly submerge the sealing edge beneath the level of the sealing liquid, and a further object is to improve 25 the construction of sealing bells and provide as great an edge surface as possible at the submerged bottom edge thereof under which the gas may escape in bubbles into the main.

With these, and other objects in view the 30 invention is illustrated in the accompanying drawing, wherein:—

Figure 1, shows a front view of a portion of the hydraulic main; the upper ends of two standpipes entering the main and also shows in broken lines the improved sealing 35 bells suspended in the main around the standpipe ends. Fig. 2, illustrates the same in vertical cross-section. Fig. 3, shows one of the detached sealing bells in perspective. Fig. 4, illustrates in top plan, an enlarged 40 detail of the sealing bell sustaining means on the upper side of the hydraulic main, and Fig. 5, shows a vertical sectional detail of the same.

Referring particularly to Fig. 3, of the 45 drawing it will be noted that the sealing bell has a flat top plate 6, with a plurality of perforations 7, therein. A boss 8, encircles each perforation at both the upper and lower side of the top plate, as seen clearly 50 in Fig. 5, of the drawing, and the surfaces of these bosses are machined so as to make them parallel.

In the present instance each bell is pro-

vided with a vertically depending front wall 9, and a similarly depending side wall 10, 55 while at the rear and other side, the walls of the bell have straight depending portions 11, and outwardly-extending hollow portions 12. These hollow portions all communicate with the space directly beneath 60 the top, and the lower edges of all the bell walls, including the straight walls and the edges of the extension are flush and in the same horizontal plane. By means of this improved construction of bell a very considerable lower edge surface is provided without materially increasing the size of the bell itself thereby affording a large edge surface beneath which the gas may bubble.

The hydraulic main is provided with a 70 top plate 13, which has a plurality of circular enlargements 14, on its upper side, and each enlargement has a concave recess 15, in its upper side, as clearly shown in detail in Fig. 5, of the drawing. An opening 16, is provided in the center of each concave recess so that a sustaining bolt 17, may be passed through said opening and have its lower end engaged with the top 6, of the bell beneath it. Each bolt 17, is accurately made and has a collar 18, near its lower end which seats on the machined upper surface of one of the bell bosses 8, while a nut 19, screws onto the lower end of each bolt and is seated against the boss on the 85 under side of the bell top. In this way the bolts are secured to the top of the bell so they will extend upwardly therefrom and at a right angle thereto. The bolts 17, are of uniform length and their upper ends 20, 90 are flattened so as to be at a right angle with respect to the length. Screw threads 21, are provided on the bolts for a purpose now to be explained.

In the concave recess 15, there is seated a 95 knuckle 22, having a convex under surface 23, which accurately fits the recess like a ball in a socket. This knuckle has a squared head 24, on its upper side through which a screwthreaded perforation 25, centrally 100 extends. A cavity 26, extends upwardly in the center of the knuckle body which cavity registers with the opening 16, in the recess of the circular enlargement 14. The knuckle-cavity 26, is passed down over the 105 upper end of the bolt 17, and the threads

in the perforation 25, are screwed onto the upper end of said bolt, during which operation the convex lower side 23, of the knuckle turns in the concave recess 15.

5 To insure accurate adjustment of the bell in the hydraulic main, it is only necessary to rotate the squared heads 24, on the knuckle so as to raise or lower the bolts 17, which carry the bell, and as the bolts and 10 the parts they coact with are accurately and uniformly made, a spirit level placed on the flat upper ends of the bolts will determine the accuracy in the adjustment of the bell at the lower ends of the bolts.

15 The hydraulic main is provided with a series of cleaning pockets 27, through which access to the main may be gained.

The standpipes, or the upper sections 28, thereof, preferably have a top cap 29, and 20 a front cap 30, both of which may be removed for cleaning purposes, and in the present instance a branch 31, of each standpipe passes through the under side of the hydraulic main and has its upper open end 25 32, terminating beneath a sealing bell of my improved construction.

It is immaterial whether the standpipe itself enters the hydraulic main or is provided with an upper section with a branch 30 31, that enters the main, the fact remains that the outlet from the standpipe is covered by the improved sealing bell.

Having described my invention what I claim is:

35 1. The combination with a standpipe of a gas retort; a hydraulic main with which the standpipe communicates; a sealing bell over the discharge-end of the standpipe; knuckles having a universal connection with 40 the hydraulic main and bolts pendants carried by the knuckles and having their lower ends rotatably engaging the sealing bell.

2. The combination with a standpipe of a gas retort; a hydraulic main with which 45 the standpipe communicates; a sealing bell over the discharge-end of the standpipe; knuckles having a universal connection with the hydraulic main and a bolt extending through each knuckle and having a stop device on its lower end said stop devices on 50 each bolt being accurately and similarly distant from the outer ends of the bolts and said stop devices being held sealed against the bell wall and rotatable with respect thereto.

55 3. The combination with a standpipe of a gas retort; a hydraulic main with which the standpipe communicates; a sealing bell over the discharge-end of the standpipe and 60 a plurality of rotatable bolts passing through the hydraulic main said rotatable bolts having their outer ends squared and dressed off accurately at a right angle to the bolt length

and the inner ends of the bolts being rotatably connected to the bell.

65 4. The combination with a standpipe of a gas retort; a hydraulic main in which the discharge-end of the standpipe projects; and a sealing bell in the hydraulic main and over the discharge-end of the standpipe,— 70 said sealing bell having a series of outwardly-extending hollow projections and straight depending portions separating said hollow projections and the bottom edges of said projections and straight portions being 75 in the same plane.

5. The combination with a standpipe of a gas retort; a hydraulic main with which 80 said standpipe communicates; a sealing bell having a flat top and a plurality of hollow extensions around the side thereof, and a plurality of adjustable suspending devices engaging the top of the bell.

85 6. The combination with a standpipe of a gas retort; a hydraulic main with which said standpipe communicates, and a sealing bell in and spaced from the top of the hydraulic main and over the discharge-end of the standpipe said sealing bell having a series of hollow extensions projecting therefrom which extensions are permanently closed on the sides and top.

90 7. The combination with a standpipe of a gas retort; a hydraulic main with which the standpipe communicates; a top for said main said top having concave recesses therein; heads having convex surfaces to seat in the top recesses; a rod passing through each head and a sealing bell in the main and sustained by said rods.

95 8. A gas sealing bell having a top with sustaining perforations therein said bell also having a series of separated depending portions that produce a series of hollow extensions.

100 9. A gas sealing bell having a series of imperforate and separated hollow extensions at its side and provided with means at its top for sustaining it.

105 10. A gas sealing bell having depending portions in its side and hollow extensions also in its side that are separated by the depending portions said bell also having means at its top for sustaining it.

110 11. A gas sealing bell having a top with boss-encircled perforations therein,—the faces of the bosses at said perforations being parallel and said bell also having hollow extensions at its sides.

115 In testimony whereof I affix my signature 120 in presence of two witnesses.

HOWARD BRUCE.
